UNITED STATES PATENT OFFICE.

EL DORADO JONES, OF MOLINE, ILLINOIS.

ATTACHMENT-PLUG.

1,141,686.

Specification of Letters Patent

Patented June 1, 1915.

Application filed May 7, 1914. Serial No. 836,848.

To all whom it may concern:

Be it known that I, EL DORADO JONES, a citizen of the United States of America, and a resident of Moline, in the county of Rock Island, State of Illinois, have invented certain new and useful Improvements in Attachment-Plugs, of which the following is a specification.

This invention relates to that type of attachment plugs used to make electrical connection between the flexible conductors or portable electrical appliances and the wall sockets of buildings. And the present improvement has for its object to provide a simple and efficient structural formation and arrangement of parts in an attachment plug of the class described, combining the features of the ordinary non-separable plug and the ordinary separable plug, and in which the extended jump spark usual to the ordinary non-separable plug is reduced to a minimum with a corresponding reduction in the high tension impulse which is sent through the electrical appliance, and the consequent corrosion of the metal portions of the plug due to the same, all as will hereinafter more fully appear.

In the accompanying drawings: Figure 1, is an enlarged central section of an attaching plug, embodying the present invention, with the parts in an electrically connected position. Fig. 2, is a similar view, with the parts in an electrically disconnected position. Fig. 3 is a cross-section on line $x-x$, Fig. 1. Fig. 4, is a similar view on line $x'-x'$ Fig. 1.

Similar reference numerals indicate like parts in the several views.

Referring to the drawings, 1 represents the outer shell or housing of the plug, formed of any usual and suitable non-electric material, and having a central bore forming a receiving cavity in which the hereinafter described movable head or member is slidingly mounted. Said parts are held from independent rotation by any usual non-circular formation of the periphery of said movable head and a corresponding formation of the central bore of said shell 1, preferably by a longitudinal groove and spline formation 2 and 3 on the respective parts, as shown more particularly in Figs. 3 and 4.

4 is a head closing one end of the central bore of the shell and provided with a pair of orifices for the reception of the ends of

the pair of resilient contact fingers or bars 5 and 6, of the shell or housing 1. Said contact fingers are secured to the head 4, and to the wires of the usual flexible conductor 7, and in the present improvement said resilient contact fingers 5 and 6 are disposed in parallel and separated relation and extend into the central bore of the shell 1, for electrical engagement with the hereinafter described pair of contact fingers of the movable head of the plug, above referred to.

8 is a cap or cover screwed or otherwise secured to the shell 1 to cover and conceal the above described connections between the head 4, contact fingers 5, 6, and wires of the flexible conductor 7, as usual in the present class of plugs. Said cap or cover 8 is formed with the usual central orifice for the passage of the flexible conductor 7, as usual in the present class of plugs. Said cap or cover 8 is formed with the usual central orifice for the passage of the flexible conductor 7 as shown in Figs. 1 and 2.

9 is a spirally fluted casing fixedly attached to the periphery of the shell 1, at the end opposite to the head 4, and adapted to screw into an ordinary lamp socket of a building or other structures. In the present improvement the casing 9 is electrically connected with a longitudinal contact strip 10 secured to one side of the central bore of the shell or housing 1, aforesaid.

11 is the movable head or number, above referred to, and which is formed of any usual and suitable non-electric material. Said head 11 is adapted to slide in one direction in the central bore of the shell 1, under the influence of a spring 12, preferably of the spiral type shown, and disposed between one end of the head 11 and the closure head 4, of the shell 1, as shown in Figs. 1 and 2. The head 11 has a movement in an opposite direction to that above described, as the shell 1 is screwed into place in an ordinary fixed socket, due to an abutment of its end against the bottom of said socket.

13 and 14, are a pair of contact fingers carried by the movable head or member 11, and arranged in parallel relation, preferably, in individual longitudinal passages formed therefor in said head or member 11. The contact finger 14 is provided with a right-angle contact flange or plate 15, which is fixedly secured to one end of the head or member 11 to constitute a terminal adapted

to contact with the usual main line terminal at the bottom of an ordinary socket. The other contact finger 13 is extended laterally through the head or member 11 and has 5 sliding contact with the above described longitudinal contact strip 10 of the shell or housing 1. As before stated said strip 10 has electrical connection with the spirally fluted casing 9, which in turn is adapted to 10 have electrical contact with the annular terminal of a stationary lamp socket of the building.

In the present construction the contact fingers 5, 6 and 13, 14 above described, are 15 arranged in alined contacting pairs, which when the attachment plug is withdrawn from the lamp socket, are forced out of electrical contact by the spring 12 aforesaid. With the introduction of the attachment 20 plug into place, the aforesaid pairs of contact fingers are simultaneously brought toward each other, to simultaneously establish electrical connection between the respective pairs of contact fingers, and with such simultaneous attainment of the respective 25 connections, the usual sparking and high tension impulses sent along the line are reduced to a minimum.

Having thus fully described my said invention, what I claim as new and desire to 30 secure by Letters Patent, is:—

1. In an attachment plug, the combination of a pair of members formed to fit and have electrical connections with the terminals of a stationary socket, one of said members being movably mounted in the other member, a spring tending to move said movable member in one direction, and resilient contact fingers carried by said members 35 and disposed in pairs adapted to be brought into electrical connection when the movable member has movement against the spring, aforesaid, individual fingers of the respective pairs having connection with the respective terminals of the plug, substantially as set forth.

2. In an attachment plug, the combination of a pair of members formed to fit and have electrical connections with the terminals of a stationary socket, one of said mem- 50 bers

bers being slidingly mounted in a non-revoluble manner in the other member, a spring tending to move said movable member in one direction, and resilient contact fingers carried by said members and disposed in pairs and adapted to be brought into electrical connection when the movable member has movement against the spring, aforesaid, individual fingers of the respective pairs having connection with the respective terminals of the plug, substantially as set forth.

3. In an attachment plug, the combination of a pair of members formed to fit and have electrical connections with the terminals of a stationary socket, one of said members being movably mounted in the other member, a spring tending to move said movable member in one direction, and a plurality of longitudinally arranged resilient contact fingers carried by said members and disposed in alined pairs adapted to be brought into electrical connection when the movable member has movement against the spring, aforesaid, individual fingers of the respective pairs having connection with the respective terminals of the plug, substantially as set forth.

4. In an attachment plug, the combination of a pair of members formed to fit and have electrical connections with the terminals of a stationary socket, one of said members being slidingly mounted in a non-revoluble manner in the other member, a spring tending to move said movable member in one direction, a plurality of longitudinally arranged resilient contact fingers carried by said members and disposed in alined pairs adapted to be brought into electrical connection when the movable member has movement against the spring, aforesaid, individual fingers of the respective pairs having connection with the respective terminals of the plug, substantially as set forth.

Signed at Chicago, Illinois, this 4th day of May, 1914.

EL DORADO JONES.
